UNITED STATES PATENT OFFICE

2,380,408

PROCESS FOR TREATING MARINE OILS

Loran O. Buxton, Belleville, N. J., assignor to National Oil Products Company, Harrison, N. J., a corporation of New Jersey

No Drawing. Application February 20, 1942,
Serial No. 431,697

2 Claims. (Cl. 260—420)

This invention relates to the treatment of marine oils and more particularly to the refining of fat-soluble vitamin-containing marine oils.

Various processes have been proposed for hydrogenating vitamin-containing marine oils to effect deodorization and stabilization thereof. In accordance with most of these proposals, the hydrogenation is carried to a point where a very substantial portion of the highly unsaturated fatty acids is partially or completely hydrogenated with a consequent decrease in the iodine value of the oil. In substantially all cases when vitamin-containing oils are treated by such processes, a portion of the vitamins is destroyed and oftentimes a very substantial amount is lost; consequently, such processes have not met with any considerable degree of commercial success.

Other processes have been proposed wherein the vitamin-containing marine oil is hydrogenated under more mild conditions, so that while some deodorization does take place, the vitamin content of the oil is not deleteriously affected to any great extent. In most cases these processes of deodorization have been carried out at pressures equal to or greater than atmospheric pressure, and at temperatures usually not above about 70° C. as it was believed that the vitamins would be deleteriously affected if the temperature was allowed to go much above about 80° C. to 90° C. However, marine oils which are so treated oftentimes still have a fishy taste and odor in addition to containing certain constituents which, although they themselves are not odoriferous or objectionable to any great extent, tend to develop into highly undesirable, obnoxious and odoriferous materials which greatly detract from the value of the vitamin-containing oil.

It has been found that the treatment of fat-soluble vitamin-containing marine oils with certain types of organic solvents yields valuable highly potent extracts containing a portion of the fat-soluble vitamins along with the bulk of the antioxidants originally contained in the oil. Thus fat-soluble vitamin-containing oils containing at least 2% unsaponifiable matter may be subjected to extraction with hot methanol or ethanol and the mass then cooled, whereby an alcoholic layer separates containing dissolved therein an oil having a much higher vitamin potency than the original oil; this process is more fully described and claimed in my copending application Serial No. 321,409, filed February 29, 1940, now Patent No. 2,347,460, dated April 25, 1944. Highly potent fat-soluble vitamin extracts

may also be obtained by contacting a fat-soluble vitamin-containing oil with a suitable solvent at a temperature at which at least the major portion of the oil is miscible with the solvent and then cooling the mixture, whereby a solvent layer containing the desired extract separates. Among the solvents which were found to be particularly suitable for use in this latter process are those listed in the table below:

Table I

1. Aliphatic and alicyclic monohydroxy alcohols containing from 3 to 6 carbon atoms.
2. Esters of said alcohols with aliphatic monocarboxylic acids, said esters containing not more than 8 carbon atoms.
3. Aliphatic and alicyclic aldehydes containing not more than 6 carbon atoms.
4. Aliphatic ketones containing not more than 6 carbon atoms.

It will be noted that these preferred solvents are all liquid organic compounds having the properties of being miscible with fatty oils at temperatures above room temperature and partially immiscible therewith at temperatures substantially below room temperature; experiments in this connection have shown that solvents of this class may be used generally in the process hereinabove described. This process is disclosed and claimed in copending application Serial No. 343,558, filed July 2, 1940, in the name of Dom-brow.

It is the object of this invention to provide an improved process for the refining of fat-soluble vitamin-containing marine oils.

A further object of this invention is to provide an improved process for the hydrogenation of vitamin-containing marine oils to improve the taste and odor thereof.

Still another object of this invention is to provide improved vitamin-containing marine oils.

Another object of this invention is to provide a process whereby all the valuable constituents of vitamin containing marine oils may be utilized.

Other objects of the invention will in part be obvious and will in part appear hereinafter.

I have found that the above and other objects of the invention may be accomplished by treating a crude or partially refined fat-soluble vitamin-containing marine oil with hydrogen under such conditions that the iodine number of the oil remains substantially unchanged, but that the odoriferous constituents in the oil are converted

to forms in which they are unobjectionable, the conditions also preferably being such that there is a tendency for certain side reactions to take place, particularly the formation of fatty isoacids and glycerides thereof which have a melting point considerably higher than their corresponding normal fatty acids and glycerides. If desired, the oil may be treated, prior to hydrogenation, by a process similar to the processes of either of the two hereinabove identified applications, but in such a manner that only a proportionately small amount of the vitamin content of the marine oil is removed, but a major portion of the free fatty acids; a large part of the undesirable components in the oil responsible for the objectionable odor and taste thereof, nitrogenous compounds such as amines, and various constituents which themselves are not objectionable but tend to develop into odorous and undesirable compounds are removed along with a certain amount of the coloring matter of the oil and the majority of the natural antioxidants in the oil. Furthermore, certain constituents of the oil which might affect the hydrogenation catalyst and tend to deactivate or poison it will also be removed to a large extent by the solvent extraction.

The invention accordingly comprises the several steps and the relation of one or more of such steps with respect to each of the others, and the product possessing the features, properties and the relation of elements, which are exemplified in the following detailed disclosure, and the scope of the invention will be indicated in the claims.

In most cases when vitamin-containing marine oils are hydrogenated to remove the taste and odor therefrom, some of the unsaturated constituents are hydrogenated at the double bonds; but usually under conditions favorable for hydrogenation of double bonds, a certain amount of the vitamin content of the oil is detrimentally affected with a consequent loss of vitamin potency.

I have found that the majority of the disagreeable constituents of vitamin-containing fish oils may be hydrogenated and converted to substantially non-disagreeable substances without materially hydrogenating the unsaturated components of the oil at the double bonds or impairing the vitamin potency of the oil provided the hydrogenation is carried out at low pressures and at moderate to high temperatures, in the presence of a relatively active catalyst. Furthermore, such hydrogenating conditions are very favorable to the formation of fatty isoacids and glycerides thereof from their corresponding normal fatty acids and glycerides, particularly if relatively large amounts of catalyst are used. It is to be understood that the term "isoacids" as used herein refers to the trans form of acids in cis-trans isomerization. In most hydrogenating processes side reactions such as the formation of isoacids and isoacid glycerides are not particularly desired; however, in the present instance they are advantageous as the isoacids and their glycerides have melting points somewhat higher than the corresponding cis acids and their glycerides, e. g. elaidic acid has a melting point of about 38° C. higher than that of oleic acid. Consequently the isoacids and glycerides thereof may be removed from the oil in much the same manner as the stearins are removed, with a consequent increase in the vitamin potency of the end product. In fact the isoacids in many cases are more easily removed from the oil than are the corresponding

normal acids which have been hydrogenated although the melting points of the acids may not differ greatly. The reason for this is that the solidified isoacids have a crystalline structure which makes them more readily separable from the oil. Therefore, if desired, the hydrogenated oil may be treated to remove any isoacids and glycerides thereof that may have been formed during the hydrogenation step. Any process suitable for the removal of stearin may be used to remove the isoacids and glycerides thereof.

In carrying out the hydrogenation step of the process any suitable pressure under that of atmospheric (1 mm. to 750 mm.) may be resorted to; however, it is highly preferred to operate within the range of about one to twenty millimeters. Medium to high temperatures, i. e. from about 95° C. to about 200° C. may be maintained during the hydrogenating step and the use of an active catalyst, e. g. Raney nickel catalyst is preferred. The conditions which appear to be the most favorable for the occurrence of side reactions resulting in the formation of isoacids are temperatures of around 100° C. or above; low pressures, preferably below 20 mm.; and relatively large amounts of active catalyst, e. g. 5% of Raney nickel catalyst. In general, from 3 to 5 hours are usually sufficient to completely deodorize the oil; however, longer or shorter periods of hydrogenation may be resorted to, if desired.

In the past it has been the common belief that when a vitamin oil is treated with hydrogen in the presence of a catalyst at temperatures exceeding 100° C., rapid destruction of the vitamin content results. However, I have found that such is not the case if the hydrogenation is carried out at reduced pressures, and that when a sub-atmospheric pressure is maintained, temperatures as high as 200° C. may be used, although temperatures of about 100° C. to 170° C. are preferred. Hydrogenation of vitamin-containing marine oils in accordance with my process will produce oils devoid of fishy taste and odor without any appreciable destruction of either vitamin A or vitamin D.

Catalysts other than Raney nickel may be used as any active catalyst will suffice including, inter alia, platinum, palladium, copper-chromium oxide, and nickel on kieselguhr. Generally from about 0.2% to about 5% of catalyst is a suitable amount to use.

When the oil is treated with a solvent before the hydrogenation, the process which is used is much the same as the processes disclosed in pending applications Serial No. 321,409 (Patent No. 2,347,460) and Serial No. 343,558; i. e. the oil is contacted with a solvent at room temperature or above, the oil-solvent mixture is cooled to a temperature considerably below room temperature, e. g. 0° C. or lower, whereby two layers are formed, one being the solvent containing the constituents which it is desired to remove from the marine oil along with part of the vitamin content thereof, and also a small amount of the oil, and the other layer being the major portion of the fish oil now substantially free of undesirable components.

The principal difference between the solvent treatment step in the present invention and the two hereinabove identified inventions is that here usually only one, and seldom more than two, extractions are made. Also, in this process the solvents which are used are as a general rule ones which are somewhat less efficient extractives of the vitamins than the solvents used in the two

previously mentioned inventions. Thus, for example, in application Serial No. 343,558, when isopropanol is the solvent, it is usually preferred to use 99% isopropanol, whereas in this invention it is preferred to use 91% isopropanol. Although highly potent vitamin extracts may be obtained using 91% isopropanol, the amount of vitamins which is removed with each extraction is much less than when 99% isopropanol is used. However, the 91% isopropanol is more efficient in removing the undesirable components of the vitamin-containing marine oil than is the 99% isopropanol, and in most cases one extraction with 91% isopropanol will remove the major portion of the objectionable constituents of the oil while removing only a small portion of the vitamin content thereof. However, the residue which remains when the solvent is removed from the solvent extract, although it is very dark colored and has a disagreeable odor and taste, is of a somewhat higher vitamin potency than the original oil and contains most of the natural antioxidants originally present in the oil; consequently it is a valuable product. One of the principal uses to which it is applicable is for the fortification of and the stabilization towards oxidative changes of vitamin-containing oils used for agricultural purposes, e. g. the enriching of the vitamin content of livestock and poultry feeds where the taste and odor of the feed are not so important as in products for human consumption. Thus by the process of this invention, vitamin-containing oils highly suitable for human consumption are produced, and the by-products of the process are valuable materials suitable for other purposes. Consequently by the use of this process, it is now possible to utilize to the fullest extent and in the most advantageous manner all of the valuable constituents of vitamin-containing marine oils.

In carrying out the solvent extraction of the oil before the hydrogenation, I prefer to use a solvent selected from the group consisting of methanol, ethanol and solvents miscible with fatty oils at temperatures above room temperature and partially immiscible therewith at temperatures substantially below room temperature, particularly those of the type listed in Table I above. Thus in addition to methanol and ethanol, solvents such as n-propyl alcohol, isopropyl alcohol, n-butyl alcohol, n-amyl alcohol, isoamyl alcohol, secondary amyl alcohol, furfuryl alcohol, allyl alcohol, diacetone alcohol, β -hydroxy ethyl acetate, methyl formate, ethyl formate, ethyl acetate, methyl acetate, isopropyl acetate, glycol diformate, glycol diacetate, methyl levulinate, ethyl levulinate, methyl aceto acetate, ethyl aceto acetate, methyl furoate, vinyl acetate, furfural, propionaldehyde, crotonaldehyde, acetone, methyl ethyl ketone, acetyl acetone and propylene chlorhydrin may be used. I have found that methanol and ethanol may be most effectively used with oils containing more than 2% unsaponifiable matter; the remaining solvents may be employed with advantage with practically any vitamin-containing fatty oil, isopropanol being particularly useful by reason of its efficiency, cheapness and ready availability. Mixtures of the above solvents may also be used, if desired. In case the solvent which is being used is a quite efficient extractive for vitamins A and D, it is preferred to dilute it with water or some other non-extracting liquid miscible with the solvent so as to reduce the amount of vitamins extracted and leave the major portion of the vitamins in the treated oils. For example, it is

preferred to use 91% isopropanol instead of 99% isopropanol as has been mentioned hereinabove.

In treating the vitamin-containing marine oil with the solvent, the relative proportion of solvent to oil may vary widely; preferably the ratio of solvent to oil should be greater than one and in most cases mixtures containing between about 2% and about 25% oil are suitable. The oil and solvent are mixed, and if desired, the mixture is heated until the oil or the greater part thereof is dissolved in the solvent. In using ethanol and methanol, which are two of the preferred solvents for extracting the oil prior to the hydrogenation, the solvent and oil will not become completely miscible even when heated to temperatures considerably above room temperature, but it is not necessary that they become completely miscible as the solvent will selectively extract the constituents which it is desired to remove.

After the oil has been thoroughly contacted with the solvent so as to extract the constituents which it is desired to remove, the mixture may be permitted to cool so as to effect a separation of the materials into two layers. The temperature to which the solution is cooled may vary from about room temperature to as low as -70° C. or lower. I have found, however, that it is preferable to cool the solution with slight agitation to temperatures somewhat below about 0° C., e. g. in the neighborhood of -18° C. One layer consists chiefly of the portion of the original oil insoluble in the solvent at low temperatures. The vitamin content of this fraction is usually slightly less than that of the original oil. The solvent layer will contain the majority of the undesirable materials which it is desired to remove from the oil along with a small per cent of the vitamins in the oil and the majority of the natural antioxidants of the oil. The residue remaining after removal of the solvent from the solvent fraction may be utilized as described hereinabove or for other purposes for which it may be adapted.

The treated oil which will now be substantially free of undesirable components and substantially lighter than the original oil but possessing a slight fishy taste and odor is partially hydrogenated as set out hereinabove. The resulting oil will be a light colored, bland, odorless product containing the major portion of the vitamins present in the original oil. This embodiment of the invention, i. e. solvent extraction of the oil followed by partial hydrogenation, forms my preferred process; however, it is to be understood that in many cases a preliminary solvent extraction step is unnecessary, and that completely bland, odorless products may be obtained merely by partially hydrogenating the vitamin-containing fish-oil in accordance with this process.

The refined oil prepared by the process of this invention may be used as such or it may be saponified in the usual manner to produce vitamin concentrates substantially free of obnoxious tastes and odors, or it may be treated further in accordance with the process of either application Serial No. 321,409 or 343,558 to produce extracts having a vitamin potency far in excess of that of the original oil. When any appreciable quantities of isoacids are formed during the hydrogenation, it is particularly desirable that they be removed as by their removal the potency of the oil will, of course, be increased. Furthermore, any odors acquired during hydrogenation may be removed by any usual deodorization process, such as steam deodorization.

The oils which may be treated in accordance

After an excellent improvement 321,000 units of hydrogenated shark liver oil was made and it was extracted by the process of Example 4 and yielded 2,380,408 units of vitamin A/gm. and a iodine value of 110. The oil with this invention may be any fat-soluble vitamin-containing marine oil or mixture of such oils, e. g. cod liver oil, shark liver oil, tuna liver oil, halibut liver oil, mackerel liver oil, ling cod liver oil, sole liver oil, spear fish liver oil, sword fish liver oil, whale liver oil, sardine oil, herring oil, etc.

This process of partial hydrogenation is particularly applicable to the refining of the residual oils obtained in the extraction of vitamin-containing oils by the process of either application Serial No. 321,409 or 343,558, or by the process of my application filed concurrently herewith which involves the extraction of fat-soluble vitamin-containing marine oils at normal room temperatures or temperatures slightly above room temperature with a solvent selected from the group consisting of methanol, ethanol, n-propanol, isopropanol, methyl acetate, ethyl acetate, methyl ethyl ketone, acetone and diacetone alcohol, the last seven named solvents containing at least 10% water.

For a fuller understanding of the nature and objects of the invention, reference should be had to the following examples which are given merely to further illustrate the invention and are not to be construed in a limiting sense, all parts given being by weight.

Example I

25 parts of shark liver oil containing 100,000 units of vitamin A/gm. having a fishy taste and odor were mixed with 0.25 part of Raney nickel catalyst and the mixture completely deaerated. The same was treated with a steady supply of hydrogen at 180° C. for one hour under a pressure of 8 mm. The treated oil was slightly lighter in color than the original oil and completely devoid of taste and odor, and the vitamin potency was the same as that of the untreated oil.

Example II

25 parts of shark liver oil containing 66,000 units vitamin A/gm. having a fishy taste and odor were mixed with 0.5 part of activated platinum oxide catalyst and the mixture deaerated and then heated at 98° C. under a pressure of 10 mm. for two hours in the presence of hydrogen gas. The mixture was cooled and the catalyst removed. The oil was odorless, completely devoid of any fishy taste, and the vitamin potency was unchanged.

Example III

500 parts of crude shark liver oil containing 100,000 units vitamin A/gm. were mixed with 10 parts of Raney nickel catalyst and heated at 100° C. for six hours under a pressure of 10 to 15 mm. in the presence of hydrogen gas. The treated oil was free of fishy tastes and odors and slightly lighter in color than the original oil, and the vitamin potency was the same as before treating. On cooling the oil, a crystalline-like material which resembled elaidic acid (iso-oleic acid) separated from the solution. The cloud and pour point of the oil was appreciably higher than that of the original oil.

Example IV

25 parts of shark liver oil containing 100,000 units of vitamin A/gm. having a fishy taste and odor were mixed with 1 part of Raney nickel catalyst and the mixture heated at 100° C. for 30 minutes under a pressure of 10 mm. in an inert atmosphere to deaerate the oil and free it from peroxides, etc. Hydrogen gas was then passed

through the oil under the same conditions for 5 hours. The catalyst was removed by filtering. The treated oil was completely devoid of odor and taste. Although the iodine value was practically unchanged, the pour point of the oil had increased considerably because of the formation of isoacids.

Example V

10 A crude shark liver oil containing 103,000 units of vitamin A/gm. was extracted twice with isopropanol by contacting the oil with the isopropanol, cooling the mixture to a temperature of about -18° C. and separating the solvent layer from the oil immiscible therein. 50 parts of the oil, immiscible with the solvent at the low temperature, which contained 97,000 units of vitamin A/gm. were mixed with 1 part of Raney nickel catalyst and the mixture heated at 150° C. under a pressure of 15 mm. in the presence of hydrogen for one hour. The mixture was cooled and filtered to remove the catalyst. The resulting product, which contained the major portion of the vitamins present in the original oil, was a bland-tasting oil completely devoid of fishiness.

Example VI

200 parts of tuna liver oil containing 67,000 units of vitamin A/gm. and 20,000 units of vitamin D/gm. were extracted three times with methanol by contacting the oil with the methanol at about 50° C., cooling the mixture to about -18° C. and separating the supernatant solvent layer from the immiscible oil layer. 50 parts of the oil immiscible with the solvent at the low temperature and possessing a fishy taste and odor were treated further essentially as described in Example V. The resulting oil which contained the major portion of the vitamin A and D content present in the original oil was free from fishiness and was light in color.

Example VII

100 parts of the immiscible oil resulting after extracting crude halibut liver oil twice with 91% isopropanol at -18° C. and which possessed a fishy taste and odor were mixed with 3 parts of a nickel catalyst on aluminum oxide, and the mixture heated to 170° C. for 5 minutes under a pressure of 5 mm. in the presence of N₂ gas to deaerate the oil. Hydrogen gas was then passed through the oil-catalyst mixture under the same temperature and pressure conditions for 20 minutes. The mixture was then cooled to room temperature and filtered to remove the catalyst. The resulting oil was completely devoid of fishiness and contained the major portion of the vitamins present in the original oil.

It will be evident from the above description and examples that this invention provides an efficient process for the utilization in the most advantageous manner of all of the valuable constituents in vitamin-containing fish oils.

Since certain changes may be made in carrying out the above process without departing from the scope of the invention, it is intended that all matter contained in the above description shall be interpreted as illustrative and not in a limiting sense.

Having described my invention, what I claim as new and desire to secure by Letters Patent, is:

1. A process of refining a vitamin-containing oil and improving the taste and odor thereof, which comprises contacting a fat-soluble vitamin-containing marine oil with hydrogen in the presence of an active hydrogenation catalyst at a

temperature between about 90° C. and 200° C. under a pressure of about 1 to 20 mm. for a period of time insufficient to affect the iodine value thereof.

2. A process of refining a vitamin-containing oil and improving the taste and odor thereof, which comprises contacting a fat-soluble vita-

min-containing marine oil with hydrogen in the presence of an active hydrogenation catalyst at a temperature between about 100° C. and 170° C. under a pressure of about 1 to 20 mm. for a period of time insufficient to affect the iodine value thereof.

LORAN O. BUXTON.
